ABSTRACT: A guard fitting between a loader bucket and the forward ends of the lift arms which support the bucket to prevent debris which is projected upwardly behind the bucket from engaging and damaging hydraulic lines employed to convey fluid under pressure from a source on the loader tractor to the hydraulic jacks carried by the bucket to adjust the parts thereof.

**GUARD FOR HYDRAULIC LINES ON A LOADER
BUCKET**

Some tractor mounted loaders are of very heavy and rugged design to enable their effective use in demolition work. In building demolition, the materials handled by a loader are of many shapes and sizes varying from bricks and cement blocks or chunks to boards, steel structural members and reinforcing rods. Some demolition bucket loaders are provided with a cover or clamp for the bucket which is actuated by hydraulic jacks on the bucket and fluid under pressure from the tractor. Hydraulic lines extend from the tractor along the length of the lift arms and must bridge the gap between the lift arms and the bucket to supply fluid to jacks on the bucket. These lines are subject to frequent breakage particularly where they bridge the gap between the lift arms and the bucket and especially because the bucket is used sometimes as a battering implement as for example in breaking down a wall of brick or other material. In the course of the many uses to which the bucket is put, it is not uncommon for material to pass behind the bucket in the vicinity of the hydraulic lines and sometimes long members of wood or steel extend upwardly through the gap to break lines and even to damage the radiator or other forwardly mounted tractor components.

The present invention provides a simple and effective guard which closes the space between the forward ends of the lift arms and which is of very simple construction and capable of being easily and inexpensively installed on existing loaders when it is contemplated that they are to be used in demolition work. A more complete understanding of the invention will be had upon reading the following specification wherein the invention is described in detail by reference to the accompanying drawing.

In the drawing:

FIG. 1 is a view in side elevation of a demolition type bucket showing the forward portion of the lift arms by which it is supported and showing a part of the lift assembly, and the mechanism of the present invention in section taken on the line I-I of FIG. 2; and

FIG. 2 is a plan view of the forward ends of the lift arms shown in FIG. 1 showing the manner of their connection to the bucket as well as the connection of the guard of the present invention to the lift arms, parts being shown in section.

The loader bucket shown in the drawing comprises a main bucket portion 10 pivotally supported at the end of a pair of lift arms 12 as by pivot pins 14. This bucket has a cover or clamp 16 pivotally supported as by pins, one of which is shown at 18 and capable of being swung about its pivotal support, between an open position and the closed position illustrated in FIG. 1, by hydraulic jack means (not shown) except for a portion of a piston rod 20 connected by pivot means 22 to the

bucket. The jack cylinder is positioned beneath a protective covering 24 on the clamp 16.

Between their forward ends, the lift arms are connected by a structural brace 26 which stops short of the bucket and leaves an opening through which material being handled can project so that flexible conduits shown at 28, which communicate fluid under pressure to the clamp actuating jack are subject to frequent damage.

The present invention provides guard means to close the opening between the brace 26 and the bucket. This guard means comprises a plate 30 reinforced by a transverse brace 31 and longitudinal braces 32. The guard is supported between the bucket and the member 26 at its forward end by bosses 34 welded to the braces 32 and fitting over the inner ends of the pivot pins 14. The normal pivot pins are replaced by longer pins for this purpose. At its rear edge the plate 30 of the guard rests upon the top of the member 26 and the braces 32 as well as smaller braces shown at 36, are formed with lugs, one of which is best shown at 38 in FIG. 1 to underlie the member 26 so that its forward end is embraced by members of the guard. Thus, the guard is capable of being quickly installed without the necessity of welding or securing means other than those produced by its own configuration.

We claim:

1. In a loader bucket which comprises a material handling bucket pivoted by pivot means to the ends of a pair of lift arms which are supported by a tractor for vertical swinging movement and a crossmember secured between said arms at a point spaced from the bucket, the improvement which comprises guard means removably mounted in said loader bucket and entirely closing the space between the arms and between the bucket and the crossmember to prevent debris from passing upwardly directly behind the bucket.

2. The improvement of claim 1 in which the guard means is supported by said pivot means.

3. In a loader bucket assembly which comprises a material handling bucket pivotally connected to the ends of a pair of lift arms by a pair of pins, which lift arms are supported by a tractor for vertical swinging movement and have a crossmember extending between them at a point spaced from the bucket, the improvement which comprises a removable guard means closing the space between the lift arms and between the bucket and the crossmember and having generally C-shaped members at the rearward edge thereof which engage the crossmember for support of said guard means at said rearward edge.

4. The improvement of claim 3 in which the guard means includes bushings at the forward edge thereof engaging the pins for support of said forward edge.
